CURRENT INTERRUPTING APPARATUS

Charles L. Stroup, Oak Park, Ill.

Application December 26, 1939, Serial No. 311,034

7 Claims. (Cl. 175—30)

My invention relates generally to electrical apparatus and it has particular relation to current interrupting apparatus such as lightning arresters, circuit breakers, and fuses, in which arc extinction is effected by means of a blast resulting from the creation of the arc and acting to blow out the arc.

This application is a continuation-in-part of my co-pending application, Serial No. 256,638, filed February 16, 1939.

An object of my invention is to provide for assisting in extinguishing an arc in a new and improved manner by directing across its path a blast created as a result of the arc.

Another object of my invention is to confine under pressure in an arc space a gas generated as a result of the creation of an arc during a period of maximum current flow therethrough and to release the gas in the form of a blast across the arc path during a period of minimum current flow to deionize the same and prevent restriking of the arc.

Still another object of my invention is to provide for drawing an arc in a relatively small arc passageway and to direct through a relatively large blast passageway and across the relatively small arc passageway a blast of gas generated by the arc for deionizing the arc path.

A further object of my invention is to provide for drawing an arc in a relatively small arc passageway during a period of maximum current flow therethrough and at the same time confining under pressure in the arc space a gas generated as a result of the arc and then releasing the gas in the form of a blast through a relatively large blast passageway and across the relatively small arc passageway during a period of minimum current flow to deionize the arc path and prevent restriking of the arc.

Other objects of my invention will, in part, be obvious, and in part appear hereinafter.

Accordingly, my invention is disclosed in the embodiments thereof shown in the accompanying drawings, and it comprises the features of construction, combination of elements and arrangement of parts which will be exemplified in the description hereinafter set forth and the scope of the application of which will be indicated in the appended claims.

While I have chosen to disclose my invention as employed in a lightning arrester, it will be apparent that it may also be employed for use in other types of current interrupters, such as fuses or circuit breakers, for interrupting alternating current at power frequency, i. e., 60 cycles, as illustrated in my copending application, Serial No. 293,237, filed September 2, 1939, the disclosure in which is intended to form a part of and to be included in the instant disclosure.

For a more complete understanding of the 60

nature and scope of my invention, reference may be had to the following detailed description, taken in connection with the accompanying drawings, in which:

5 Figure 1 is a vertical sectional view of a lightning arrester unit illustrating the principles of my invention;

Figure 2 is a vertical sectional view through a lightning arrested unit illustrating a working embodiment of my invention;

Figure 3 is a sectional view taken on line 3—3 of Figure 2;

Figure 4 is a sectional view taken on line 4—4 of Figure 2; and

15 Figure 5 is a view, partly in vertical section and partly in side elevation, of a complete lightning arrester illustrating another embodiment of my invention.

With a view of illustrating the principles of my invention, reference may now be had to Figure 1 of the drawings in which the reference character 10 designates, generally, a lightning arrester unit comprising a fiber casing 11 and upper and lower electrodes or terminals 12 and 13.

20 The electrode 12 has a boss 14 depending from the under side thereof and the discharge voltage of the lightning arrester unit 10 is determined by the distance between the boss 14 and the lower electrode 13. A block of fiber material 15 is disposed within the casing 11 adjacent to the lower electrode 13 and spaced from the upper electrode 12 to provide a chamber 16. In order to provide an air gap between the boss 14 and electrode 13 an arc passageway 17 of relatively small area or bore is formed in the fiber block as shown. A blast passageway 18 of relatively greater length and area than the arc passageway 17 is provided diagonally through the fiber block 15, terminating in the chamber 16 and at the aperture or hole 19 provided in the lower electrode 13. The passageway 18 comprises a blast passageway for the discharge of gases generated by the arc transversely of the arc in the arc passageway 17. The upper electrode 12 and the lower electrode 13 may be connected to line and ground respectively, as shown.

25 While the blast passageway 18 is illustrated as terminating in the aperture 19 of the lower electrode 13, it will be understood that it may terminate otherwise. For example, it may vent directly through the side wall of the casing 11. The principal requirement is that the gas which is evolved from the fiber block 15 during a period of maximum current flow and confined under pressure in the chamber 16 be able to discharge in the form of a blast across the arc passageway 17 during a period of minimum current flow for deionizing at least a portion of this arc passageway and preventing restriking therethrough.

30 A metallic conductor in the form of a plug in

passage 17 immediately above the intersection of passageways 17 and 18 may be utilized to insure an upward flow only of the gas generated in the upper end of the passage 17. This prevents escape of the gas there generated directly into the passage 18. In this construction the arc obviously is formed in two sections. The same feature may be introduced into the embodiment shown in Figures 2, 3, 4 and 5.

The function and operation of the lightning arrester unit 10 will be seen to be as follows: When a voltage equal to or greater than that of the discharge voltage is impressed on the lightning arrester unit 10, an arc will be formed between the boss 14 and the electrode 18 through the arc passageway 17. The heat of the arc thus established will evolve gases, substantially water vapor, from the surfaces of the fiber casing 11 and block 15 as is well understood by the art in connection with fuses and other electrical protective devices. The evolution of the hot gases is so rapid that a high pressure will be set up in the chamber 16 and the hot gases will be expelled through the blast passageway 18 with tremendous velocity and pressure. Any part of the original arc carried over or transferred into the blast passageway 18 will be extinguished therein by the hot gases expelled therethrough. The passageways 17 and 18 intersect each other as shown, and the hot gases expelled through the blast passageway 18 with such tremendous velocity and pressure, immediately on crossing the arc passageway 17 at the intersection, extinguish the arc established in the arc passageway 17. The function and operation of the lightning arrester unit 10 on discharge will be seen to be analogous to that of allowing an arc to be formed between electrodes separated by a short air gap through fiber material and then exposing a short length of the arc and blowing a violent blast of arc extinguishing gas across the space which is exposed so that the space is deionized and the arc cannot sustain itself in that region and is extinguished. Such action is carried out automatically in the lightning arrester unit 10 by having the short arc passageway 17 of small area intersecting the longer passageway 18 of greater area.

I have found that the working embodiment of my invention shown in connection with Figures 2, 3, and 4 of the drawings has certain practical design characteristics which are superior to the embodiment shown in Figure 1. Referring now particularly to Figures 2, 3, and 4 of the drawings, a lightning arrester unit is designated, generally, at 25 which has the same general operating characteristics as those described hereinbefore in connection with the lightning arrester unit 10 of Figure 1. The lightning arrester unit 25 comprises a fiber housing or casing 26 with an upper electrode 27 and a lower electrode 28 closing off the upper and lower ends respectively of the housing 26. A boss 29 projects from the under side of the upper electrode 27 to fix a definite spot from which an arc may be established. The discharge voltage of the lightning arrester unit 25 is determined by the distance between the boss 29 and the lower electrode 28. A cylindrical fiber block 30 is provided within the housing 26 resting on the lower electrode 28 and spaced from the upper electrode 29 to form a chamber 31. A set screw 32 may be provided in a path in the upper electrode 27 to maintain the fiber block 30 in position.

In order for the lightning arrester unit 25 to

have the same general operating characteristics as the lightning arrester unit 10 of Figure 1, passageways are provided therein corresponding to the passageways 17 and 18 of the lightning arrester unit 10. The narrow space, indicated at 33, between the side of the fiber block 30 and the inner surface of the housing 26 constitutes a substantially direct arc passageway of constricted area between the boss 29 and electrode 28 which corresponds to the arc passageway 17, Figure 1. With a view to providing a blast passageway corresponding to the longer blast passageway 18 of greater area (Figure 1), holes 34 and 35 are drilled into the fiber block 30 as shown. The holes 34 and 35 do not communicate directly with each other, and extend only part way into the fiber block 30. The upper hole communicates with the chamber 31 and the lower hole 35 registers with an aperture or hole 36 in the bottom electrode 28.

As previously indicated, the lower hole 35 could vent through the side wall of the casing 26, if desired, rather than through the hole 36 in the bottom electrode 28.

With a view of providing a passageway to interconnect the holes 34 and 35, a groove 37 is provided in the lateral surface of the fiber block 30. It will be noted that the groove 37 is not continuous, but terminates at non-communicating ends. One end of the groove 37 is connected with the hole 34 through a small passageway 38 and the other end of the groove 37 communicates with the hole 35 through a small hole 39. The arrows 40 indicate the path followed by gases expelled from the chamber 31 out to and through the aperture 36. The blast passageway thus provided by the holes 34 and 35 and the groove 37 corresponds to the blast passageway 18 (Figure 1), but is substantially longer. Its length can be still further increased by having the groove 37 make several turns around the surface of the fiber block 30 before the ends thereof are connected to or with the holes 34 and 35. As an alternative to the groove 37 in the lateral surface of the fiber block 30, a similar groove may be provided in the inner surface of the fiber housing 26.

To complete the assembly of the lightning arrester unit 25, a line terminal 41 may be provided which screws into a tap in the upper electrode 27, and a ground terminal 42 may be provided which screws into the lower electrode 28.

The operation of the lightning arrester unit 25 will be observed to be as follows: When a voltage equal to or greater than the discharge voltage is applied to the lightning arrester unit 25, an arc is formed in the narrow space 33 between the boss 29 and the lower electrode 28. The heating effect of this arc on the adjacent fiber surfaces of the housing 26 and block 30 causes hot gases to be evolved therefrom. Accordingly, a pressure will be built up in the chamber 31 and the hot gases will be expelled under high pressure through the hole 34 out into the groove 37, from the groove 37 into the lower hole 35, and out through the aperture 36, as indicated by the arrows 40. Any part of the arc between the boss 29 and electrode 28 which may be carried or transferred into the blast passageway designated by the arrows 40 will be quickly extinguished or blown out. It will be noted that the groove 37 intersects the narrow space 33 between the side of the fiber block 30 and the inside of the housing 26. The hot gases and vapors expelled through the groove 37 at tremendous velocity and

pressure extinguish and cut off the arc formed in this narrow space 33. Actual tests have shown that this arrangement of intersecting passageways will extinguish the arc on a 2300-volt circuit at the end of one or two half cycles.

Another embodiment of my invention is disclosed in connection with the lightning arrester designated generally at 50 in Figure 5 of the drawings. The lightning arrester 50, which may be mounted on a cross arm or other location, comprises an inverted porcelain cup 51 and a post type insulator 52 interconnected by a neck 53. A lightning arrester unit 54 may be disposed within the inverted cup 51 with its upper terminal 55 projecting up into a recess 56 in the side of the neck 53. A conducting member 57 projects into the recess 56 and through an aperture in the terminal 55, and is rotatable therein. The conducting member 57 carries another conducting member 58 fixedly mounted thereon. When the conducting member 58 is in a vertical position it is separated from a line terminal 59 carried on the top of the post type insulator 52 by an air gap 60. The conducting member 57 is rotatable in the terminal 55 and rests on the bottom of the recess 56. A relatively soft washer 61 is provided around the terminal 55 between the top of the lightning arrester unit 54 and the top surface of the inverted cup 51 to prevent contact therebetween. That is, tightening the lightning arrester unit 54 against the inside of the inverted cup 51 which might cause breakage thereof, is thereby prevented.

The lightning arrester unit 54 may be removed from and replaced in the inverted cup of the lightning arrester 50 as follows: To insert the lightning arrester unit 54 in the lightning arrester 50, the conducting member 58 is first rotated away from the terminal 59 by a switch stick if it has not already been so moved. The lightning arrester unit 54 is then screwed onto the bottom of the terminal 55 until the conducting member 57 is drawn down tightly against the bottom of the recess 56. The conducting member 58 is then turned up into place as shown in Figure 5 by a switch stick, and the ground terminal is connected as shown. To remove the lightning arrester unit from the lightning arrester 50, the conducting member 58 is turned down by a switch stick and the lightning arrester unit 54 is then unscrewed from the terminal 55.

It is important that the air gap 60 be provided in connection with the lightning arrester 50. If the line were directly connected to the terminal 55 of the lightning arrester unit 54, the voltage of the line to ground would be continually impressed on the lightning arrester unit 54. Such impressed voltage would cause minute currents to leak through the lightning arrester unit 54 over the fiber surfaces thereof. Such leakage currents would eventually cause the surfaces of the fiber elements in the lightning arrester unit 54 to become charred and thereby destroy the unit. It will be understood that the air gap 60 and the air gap between the upper and lower electrodes of the lightning arrester unit 54 have a lower break-down voltage than that of the transformer or other apparatus which is to be protected by the lightning arrester 50.

While I speak of an arc as though it were a single continuous arc it is to be understood that the arc referred to herein may be broken up into sections by intervening conductors.

Since certain further changes can be made in the foregoing constructions, and different em-

bodiments of the invention may be made without departing from the scope thereof, it is intended that all matter shown in the accompanying drawings or described hereinbefore shall be interpreted as illustrative and not in a limiting sense.

I claim as my invention:

1. A lightning arrester comprising, in combination, a fiber housing, an upper electrode closing off the upper end of said fiber housing, a lower electrode closing off the lower end of said fiber housing, an aperture in said lower electrode, a fiber block fitting within said fiber housing, a narrow space between the lateral surface of said fiber block and the inner surface of said fiber housing, a chamber between the top of said fiber block and said upper electrode, a groove in the lateral surface of said fiber block, an upper passageway interconnecting said groove with said chamber and a lower passageway interconnecting said groove with said aperture, said narrow space between the lateral surface of said fiber block and the inner surface of said fiber housing constituting an arc passageway of restricted area between said upper and lower electrodes, said groove and said upper and lower passageways in communication therewith constituting a blast passageway of greater area and length between said upper and lower electrodes than said arc passageway, and arc extinguishing gases being given off from said fiber housing and fiber block when exposed to an electric arc.

2. A lightning arrester comprising, in combination, a cylindrical fiber housing, an upper electrode closing off the upper end of said cylindrical fiber housing, a boss projecting from the underside of said upper electrode, a lower electrode closing off the lower end of said cylindrical fiber housing, an aperture in said lower electrode, a cylindrical fiber block fitting within said cylindrical fiber housing, a narrow space between the lateral surface of said cylindrical fiber block and the inner surface of said cylindrical fiber housing, a chamber between the top of said cylindrical fiber block and said upper electrode, a groove in the lateral surface of said cylindrical fiber block, an upper passageway interconnecting said groove with said chamber, and a lower passageway interconnecting said groove with said aperture, said narrow space between the lateral surface of said cylindrical fiber block and the inner surface of said cylindrical fiber housing constituting an arc passageway of restricted area for arcs formed between said boss and said lower electrode, said groove and said upper and lower passageways in communication therewith constituting a blast passageway of greater area and length for arcs formed between said boss and said lower electrode than said arc passageway, and arc extinguishing gases being evolved from said cylindrical fiber housing and from said cylindrical fiber block when exposed to an electric arc.

3. A lightning arrester comprising, in combination, a fiber housing, an upper electrode closing off the upper end of said fiber housing, a lower electrode closing off the lower end of said fiber housing, an aperture in said lower electrode, a fiber block fitting within said fiber housing, a narrow space between the lateral surface of said fiber block and the inner surface of said fiber housing, a chamber between the top of said fiber block and said upper electrode, a passageway extending around the lateral surface of said fiber block and intersecting said narrow space

between the lateral surface of said fiber block and the inner surface of said fiber housing, and means interconnecting said passageway with said chamber and said aperture, said narrow space between the lateral surface of said fiber block and the inner surface of said fiber housing constituting an arc passageway of restricted area between said upper and lower electrodes, said passageway extending around the lateral surface of said fiber block together with said interconnecting means constituting a blast passageway between said upper and lower electrodes, and arc extinguishing gases being given off from said fiber housing and fiber block when exposed to an electric arc.

4. A lightning arrester comprising, in combination, a fiber housing, an upper electrode closing off the upper end of said fiber housing, a lower electrode closing off the lower end of said fiber housing, an aperture in said lower electrode, a fiber block fitting within said fiber housing, a narrow space between the lateral surface of said fiber block and the inner surface of said fiber housing, a chamber between the top of said fiber block and said upper electrode, a groove in the lateral surface of said fiber block, an upper passageway interconnecting said groove with said chamber and a lower passageway interconnecting said groove with said aperture, said narrow space between the lateral surface of said fiber block and the inner surface of said fiber housing constituting an arc passageway of restricted area between said upper and lower electrodes, said groove and said upper and lower passageways in communication therewith constituting a blast passageway of greater area and length between said upper and lower electrodes, and arc extinguishing gases being given off from said fiber housing and fiber block when exposed to an electric arc, an arc being struck between said upper and lower electrodes through said arc passageway when a voltage equal to the discharge voltage of said lightning arrester unit is impressed thereon, and said arc causing said arc extinguishing gases to be evolved which drive through said blast passageway under high pressure whereby said arc is extinguished.

5. A lightning arrester comprising, in combination, a cylindrical fiber housing, an upper electrode closing off the upper end of said cylindrical fiber housing, a boss projecting from the under side of said upper electrode, a lower electrode closing off the lower end of said cylindrical fiber housing, an aperture in said lower electrode, a cylindrical fiber block fitting within said cylindrical fiber housing, a narrow space between the lateral surface of said cylindrical fiber block and the inner surface of said cylindrical fiber housing, a chamber between the top of said cylindrical fiber block and said upper electrode, a groove in the lateral surface of said cylindrical fiber block, an upper passageway interconnecting said groove with said chamber, and a lower passageway interconnecting said groove with said aperture, said narrow space between the lateral surface of said cylindrical fiber block and the inner surface of said cylindrical fiber housing constituting an arc passageway of restricted area for arcs formed between said boss and said lower electrode, said groove and said upper and lower passageways in communication therewith constituting a blast passageway of greater area and length for arcs formed between said boss and said lower electrode, and arc extinguishing

gases being evolved from said cylindrical fiber housing and from said cylindrical fiber block when exposed to an electric arc, an arc being struck between said upper and lower electrodes through said arc passageway when a voltage equal to the discharge voltage of said lightning arrester unit is impressed thereon, and said arc causing said arc extinguishing gases to be evolved which drive through said blast passageway under high pressure whereby said arc is extinguished.

6. A lightning arrester comprising, in combination, a fiber housing, an upper electrode closing off the upper end of said fiber housing, a lower electrode closing off the lower end of said fiber housing, an aperture in said lower electrode, a fiber block fitting within said fiber housing, a narrow space between the lateral surface of said fiber block and the inner surface of said fiber housing, a chamber between the top of said fiber block and said upper electrode, a passageway extending around the lateral surface of said fiber block and intersecting said narrow space between the lateral surface of said fiber block and the inner surface of said fiber housing, and means interconnecting said passageway with said chamber and said aperture, said narrow space between the lateral surface of said fiber block and the inner surface of said fiber housing constituting an arc passageway of restricted area between said upper and lower electrodes, said passageway extending around the lateral surface of said fiber block together with said interconnecting means constituting a blast passageway between said upper and lower electrodes, and arc extinguishing gases being given off from said fiber housing and fiber block when exposed to an electric arc, an arc being struck between said upper and lower electrodes through said arc passageway when a voltage equal to the discharge voltage of said lightning arrester unit is impressed thereon, and said arc causing said arc extinguishing gases to be evolved which drive through said blast passageway under high pressure whereby said arc is extinguished.

7. A lightning arrester comprising, in combination, an inverted cup of insulating material, a post type insulator disposed above said inverted cup, a neck interconnecting said inverted cup and said post type insulator, a recess in the side of said neck, a lightning arrester unit comprising upper and lower electrodes disposed within said inverted cup, a first conducting member projecting from the upper electrode of said lightning arrester unit up into the recess in said neck, a second conducting member rotatably connected with said first conductor and resting on the bottom of the recess in said neck, a third conducting member fixedly connected to said second conducting member, a terminal carried by said post type insulator, an air gap between said third conducting member and said terminal, and means for regulating the bearing pressure of said second conducting member on the bottom of the recess in said neck whereby the free rotation of said second conducting member and said third conducting member fixedly connected therewith is prevented when said lightning arrester unit is secured in position in said inverted cup, external force being required to rotate said second and third conducting members to increase the length of said air gap.
